UNITED STATES PATENT OFFICE.

HARRY HERTZBERG, OF BROOKLYN, NEW YORK, ASSIGNOR TO MORRIS PROPP, OF NEW YORK, N. Y.

DETACHABLE ELECTRIC-PLUG FITTING.

Application filed August 11, 1926. Serial No. 128,544.

This invention relates to detachable electric plug fittings.

One object of the invention is the provision of an improved switch type, multiple lamp-socket, plug fitting, having a body portion formed of molded insulating material which is adapted to receive a plurality of electric bulbs or for making connections with a plurality of electrical appliances.

Another object of the invention is to provide in a device of the character described, an improved lever switching means which may be incorporated in molded insulating attachment fittings.

A further object of the invention is to provide a lever type switch of improved construction for selectively controlling each socket of a multiple socket, plug fitting of the character described.

A still further object of the invention is to provide a fitting of the character described including an improved lever operating switching mechanism comprising few and simple parts which may be quickly and easily assembled, which shall be comparatively cheap to manufacture yet neat and attractive in appearance, and practical and efficient in operation to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention,

Fig. 1 is a cross-sectional view taken on line 1—1 in Fig. 3, showing the interior construction of an improved lever-switch type, duplex lamp-socket, plug fitting embodying the invention.

Figs. 2 and 3, respectively, are front elevational and bottom plan views of the improved fitting.

Referring in detail to the drawing, 10 denotes a duplex electric lamp-socket, plug fitting embodying the invention. Said fitting is seen to comprise a plug 11 made preferably of molded insulating material and provided with a central contact 12, said plug being con-

nected to and supporting the other parts forming the fitting in a manner hereinafter described.

The contact 12 comprises a screw 13, the shank end 13^a of which is threaded and projected through a central bore 11^a in the plug, and a conical washer plate 14. The latter is held in position in a suitable recess formed in the head end of the plug 11 by means of the screw head 13^b, as is clearly shown in Fig. 1. The threaded shank end 13^a extends into and is anchored to the body portion of the fitting 10, as shown in Fig. 1, and as will hereinafter be more fully described.

A shell 15 preferably made of sheet metal which forms an outer contact for the plug 11, is fitted over the latter from a point spaced from its outer end and is provided with a series of lips 15^a projecting inwardly against the bottom of the plug, said shell 15 also having integrally formed spaced lugs 16 and 17 extending between diametrically disposed lips 15^a. The lugs 16 and 17 have one end of conducting members 18 and 19 preferably formed of springy material, connected thereto in any suitable manner, as by means of an eyelet rivet 20, the free ends 18^a and 19^a, respectively, of said members being bent to form central spring contact members for two metallic, shell sockets 21 and 22.

The inner ends of said shells 21 and 22 are provided with lips 21^b and 22^b which fit against ledges 31 and 32, respectively, formed on said body portion sections 26 and 27, respectively, for retaining said shells against rotary movement with respect to the body portion. A projecting ledge 33 is also provided on the side of said sections abutting the inner end of the plug 11 for engaging with the latter and lips 15^a of the shell 15 to hold said plug and shell against rotary movement with respect to the body portion.

The shell sockets 21 and 22 are positioned in spaced relation to extend divergently with respect to the plug 11 and are adapted to receive the usual screw base (not shown) of electric bulbs or attachment plugs connecting with electric appliances.

For controlling the circuit from the plug to each of said sockets, a lever control switch 105 S is provided. Said switch comprises a conductor member 23 made of springy material bent to have a looped end 23^a, the bight portion of which engages the threaded end 13^a of the shank of screw member 13, and is secured 110

thereto by a nut 24. The free end portions 23^b and 23^c of the conductor member 23 are bent away from each other and normally extend along and are spaced from the outer side 5 of the screw shells 21 and 22, respectively, as is shown in full lines in Fig. 1. Mounted between said end portions 23^b and 23^c, there is a lever 25 which is adapted to have its inner end 25^a engage said portion 23^c for 10 forcing it into contact with the shell socket 22, as is clearly shown in dotted lines in Fig. 1.

For enclosing, spacing and insulating the various parts described above, an insulating casing or body portion is provided comprising 15 two similar sections or halves 26 and 27. Each section of the casing is perforated to receive suitable fastening means, such as bolts 28 and 29 for holding the elements forming the fitting 10 assembled, the bolt 28 preferably 20 passing through the loop portion 23^a of the member 23 and the bolt 29 serving as a pivotal support for the lever 25. Hollow branch portions 26^a and 26^b, and 27^a and 27^b of the sections 26 and 27, respectively, which 25 when the fitting is assembled enclose the shell sockets 21 and 22, are preferably made with grooves 30 on the interior sides thereof adjacent the end thereof to receive the outwardly flared rims 21^a and 22^a of the shells 21 and 30 22, respectively, for rigidly retaining said shells against longitudinal movement in the body portion.

The section 27 is provided with a slotted portion 27^c to permit limited movement of 35 the handle end 25^b of the lever 25 in the direction indicated by the arrow, (see Fig. 1), from a normally vertical "off" position shown in full lines to an "on" position on the dotted line position. The abutment wall 27^a of portion 27^c serves as a stop to prevent movement 40 of said lever handle end 25^b to the right.

The switching mechanism S described above is effective to control only the circuit connection from the plug 11 to the socket 22 independently of the circuit to the socket 21. For the latter, a similarly constructed switch control means is provided, said means including a lever 125 positioned alongside the lever 25 and pivoted on the bolt 29. Said lever 50 125 like lever 25 is adapted for limited movement in a slotted portion 26^c from a normally vertical "off" position, against the abutment wall 26^a, to an "on" position when moved in the direction indicated by the arrow in Fig. 3. The movement of the lever handle end 125^b 55 to the "on" position is effective to spring the end portion 23^b against the shell 21 in a manner similar to that described above for the lever 25 and the end portion 23^c, and as shown in Fig. 1 in dotted lines. The lever handle ends 25^b and 125^b are preferably formed with finger grips extending in opposite directions to facilitate independent and selective operation of the switch controls for the sockets 21

and 22, and if desired suitable indicating markings 34, such as "Off" and "On" for showing the position of the switches may be provided on the intermediate portions 26^e and 27^e on the body portion sections 26 and 27, respectively. 65 70

The casing sections 26 and 27 are provided with mating grooves 35 and 36 for receiving the conductors 18 and 19 and recesses 37 and 38 for housing the looped end portion 23^a of the member 23 and the switching mechanism S. Said grooves 35 and 36 are preferably made sufficiently wide to permit movement of the members 18 and 19 therein so that the spring ends 18^a and 19^a of said members forming the central contacts for the sockets 21 and 22, respectively, are not likely to be strained or broken when a base of a bulb or an attachment plug is screwed into said sockets, the members 18 and 19 freely flexing within the grooves to afford effective spring contact engagement in said sockets without straining. 75 80 85

It is to be understood that the detailed construction shown in the drawing and described above of the means for securing the sections and parts of the fitting 10 together may be varied, but the construction shown and described greatly expedites assembly of the fitting 10, the current carrying members being accommodated in complementary grooves formed in the sections in which they may be simply placed and the sections and parts secured together to form a rugged fitting constructed to withstand rough usage and yet afford a neat and attractive appearance to the device as a whole. 90 95 100

It will thus be seen that there is provided a device in which the several objects of this invention are achieved, and which is well adapted to meet the conditions of practical use. 105

As various possible embodiments might be made of the above invention, and as various changes might be made in the embodiment above set forth, it is to be understood that all matter herein set forth or shown in the accompanying drawing is to be interpreted as illustrative and not in a limiting sense. 110

Having thus described my invention, I claim as new and desire to secure by Letters Patent: 115

In an electric fitting, spaced current carrying receptacles, an electric switching mechanism mounted between said receptacles, said mechanism comprising a looped member having spring contact ends, each end being normally spaced from one of said receptacles, and a pair of levers positioned between said ends arranged so that each lever may be independently operated to flex one of said ends for contacting with a receptacle. 120 125

In testimony whereof I affix my signature.

HARRY HERTZBERG.
